PEGBOARD TOY

Hugo L. Swirkal, Los Angeles, Calif.

Application July 27, 1951, Serial No. 238,885

9 Claims. (Cl. 46—1)

1

This invention relates generally to the toy art and more particularly to a peg board toy in which pegs are driven by a mallet or the like through peg holes in a board. Specifically, the invention pertains to improvements in peg board toys of the type disclosed in my pending application, Serial No. 90,718, filed April 30, 1949, for peg board toy, now Patent No. 2,564,348.

Toys of the character referred to above are exceedingly popular with small children, the toy being not only amusing to the children but also a test of their dexterity. Peg boards heretofore employed have several disadvantages, the most important being that the pegs become worn and the holes through which the pegs are driven become enlarged so that eventually the pegs are not frictionally held in the holes and are quite apt to slide therethrough. When this condition prevails, the toy becomes useless and is usually discarded. In addition, it is rather difficult to manufacture such conventional peg boards so that the pegs initially have the proper fit in the holes, the reason being that the peg stock, which is purchased in finished form, may vary in diameter due to inaccurate turning of the wood, shrinkage, etc. Moreover, certain woods have varying degrees of hardness and thus possess different wear resisting qualities. Another fault of previous devices of this general type is that the pegs may be driven clear through the peg board and thus completely ejected from the board and this frequently results in misplacement and loss of the pegs.

In the highly competitive field of toy production, it is essential that the manufacturing costs be maintained at a minimum so that the toy may be sold at a low price. Consequently, the manufacture of conventional peg board toys has been continued and the many disadvantages referred to above have been tolerated in order to offer the toy at a low cost to the purchaser.

It is an object of this invention to provide a toy of the peg board type which, though it possesses many improvements and added parts, may be manufactured by mass production methods and sold at a price comparable to that of conventional peg board toys.

Another object is to provide a toy of the peg board type which includes peg board means having means incorporated therein for offering frictional resistance to movement of the pegs in the peg holes or openings so that they may be driven through the holes only when impact force of predetermined magnitude is applied thereagainst. This object is best attained by providing a peg

2

board composed of a plurality of peg board elements resiliently mounted for movement toward and away from one another and having cooperating notches in their facing edges defining the peg holes or openings in which the pegs are adapted to be driven, the device having spring means operative to normally force the elements together so as to apply lateral pressure against the pegs and thus offer frictional resistance to their axial movement in the holes. By this means, wear of the pegs or wear of the wood surrounding the peg holes is automatically compensated for and a firm engagement of the pegs is assured.

15 Another object is to provide a toy of the class referred to having two sets of peg board elements which are yieldingly spread apart, to maintain their individual elements in juxtaposition, by means of a pair of springs compressed between the sets of elements, the springs being retained in holes or pockets in the adjacent elements of the two sets. By this structure, all the peg board elements are positively urged together, to frictionally grip the pegs in the openings, 25 by the use of but two springs and this makes for economy of manufacture.

Another object is to provide a toy of the type specified which includes a pair of upright end members and a pair of longitudinal side rails secured to and extending between the end members, said rails preferably being metal and having longitudinal tongues or fins which are received in longitudinally extending slots or grooves formed in the lateral edges of the board elements. By this structure, the board elements are supported by the side rails and guided in their sliding movement so as to normally maintain them in parallelism.

Another object is to provide a device of this type in which all the board elements of each set of elements can be cut from a piece of stock of the same size as the end members so that all the wooden parts of the frame can be made from the same standard size stock to reduce the over-all cost of the article.

Another important object is to provide a peg board toy in which each of the peg board elements is provided with right-angular notches which cooperate with those of an adjacent element to provide substantially square peg openings in which square pegs, having rounded corners, are disposed and adapted to be driven by means of a mallet or like hammering tool. By this important improvement, the pegs may be 50 made from board or strip stock at a fraction of

the cost of producing conventional round pegs from expensive dowel stock. In addition, it has been found that greater frictional resistance to sliding movement of the pegs in the peg holes is effected when the pegs and openings are of square cross-sectional shape, the flat interengaging surfaces increasing the frictional contact and the pegs tending to wedge in the V-shaped notches. Thus, it is possible to employ lighter, less expensive springs for closing the peg board elements together and this results in a further saving in the cost of manufacture. Moreover, as will be readily apparent to those versed in the art, the V-shaped notches may be cut simultaneously in the edges of a plurality of the board elements by a gang of saws at a fraction of the cost of drilling circular peg holes, as is the case in conventional peg board toys.

A further object is to provide a toy of the type indicated in which is embodied a simple stop means for limiting sliding movement of the pegs in the peg openings, in either direction, so as to prevent displacement of the pegs from the board and possible loss of the pegs. This object is best attained by simply routing a longitudinal groove or depression in a side of each square peg and driving a small nail into a side of one of the notches forming a peg opening, the end of the nail projecting into the groove and being engageable with the ends of the same to limit the vertical movement of the peg.

A still further object is to provide a peg board toy which is especially attractive in appearance, strong and durable in use, very economical to manufacture by mass-production methods, and one which may be easily operated by small children, without fear of pinching their fingers between the relatively movable parts.

Further objects will appear from the following specification and from the drawing, which is intended for the purpose of illustration only, and in which:

Fig. 1 is a perspective view of my improved peg board toy;

Fig. 2 is a longitudinal sectional view through the toy, taken on line 2—2 of Fig. 1;

Fig. 3 is a cross-sectional view, taken on line 3—3 of Fig. 1;

Fig. 4 is a fragmentary plan view of a portion of a pair of adjacent board elements, showing the pegs in the peg openings;

Fig. 5 is a cross-sectional view, taken on line 5—5 of Fig. 4;

Fig. 6 is a composite perspective view of a board element and a peg; and

Fig. 7 is a view of an alternative form of peg.

Referring to the drawing in detail, my improved peg board toy includes a frame or holder having a pair of parallel, vertical end members 10 and 11 which are preferably square pieces of wood of approximately $\frac{3}{4}$ inch thickness. Disposed midway between their upper and lower ends, the vertical side edges of the end members are provided with horizontal slots 12. Connected to and extending between the end members 10 and 11 are side rails 15. These rails are preferably made as aluminum extruded T-sections having vertical flanges or webs 16 and horizontal tongues or fins 17, as best shown in Fig. 3. The portions of the fins 17 which are disposed at the ends of the rails 15 are received in the slots 12 of the end members, and wood screws 18 pass through holes in the rails and are screwed into the sides of the end members to connect the rails to the end members and provide

a strong and stable rectangular frame structure, the engagement of the fins 17 in the slots precluding relative twisting of the parts.

The side rails 15 provide supports for the lateral edge portions of a peg board which, as shown, comprises a plurality of wooden strips which are relatively slidable, longitudinally of the side rails. The peg board comprises two sets 20 and 21 of three board elements which are identified as outer elements 22 and 23, inner elements 24 and 25, and intermediate elements 26 and 27 interposed between the inner and outer elements. Each element 22 to 27 is provided with a horizontal groove 28 in each of its lateral edges, these grooves receiving the fins 17 of the side rails 15. Thus, the elements 22 to 27 are supported by the side rails and are slidable toward and away from the end members 10 and 11 and relative to one another. Preferably, although not necessarily, the outer elements 22 and 23 are secured to the end members 10 and 11 by means of wood screws 29. The board elements of each set 20 and 21 are cut from a board of the same size as the end members 10 and 11 and by this provision, the production of the toys is greatly simplified.

Each board element or wooden strip 22 to 27 is provided with a pair of V-shaped notches 30 in at least one side edge thereof, the notches having inclined sides extending at right angles to each other. The notches 30 are provided in the adjacent sides of the elements and together form substantially square peg holes or openings 31. The board elements of each set are maintained in juxtaposition and forced toward the respective end members 10 and 11 by means of coil springs 33 which, as shown in Fig. 2, are compressed between the inner elements 24 and 25 with their ends held in pockets 34 in these elements. Due to the inherent extensibility of the springs 33, each element is urged toward an adjacent element to reduce the size of the peg openings to somewhat less than the size of a true square.

Pegs 35 of square cross section are adapted to be disposed in each peg opening 31 and to be frictionally retained therein due to the action of the springs 33 in closing the elements together. The pegs 35, which have rounded corners, are inserted in the peg openings by first forcing the elements apart against the action of the springs 33 to increase the size of the openings and then sliding the pegs into place. When the board elements are released, the springs function to force the elements toward one another so as to grip the pegs in the peg openings and create sufficient frictional resistance to vertical sliding of the pegs.

After the parts have been assembled as explained above, the toy is ready for use. By the use of a wooden mallet 36, or the like, a child may hammer against the upper ends of the pegs to drive the latter downwardly in the peg openings, the frictional resistance offered by the engagement of the flat sides of the pegs along the flat sides of the notches 30 retarding the downward movement of the pegs and making it necessary to strike with considerable impact. After the pegs have been driven downwardly, the toy is inverted and the pegs are driven back in the opposite direction.

As pointed out previously, one of the disadvantages of conventional peg board toys is that it is possible to drive or pull the pegs from the board and when this occurs the displaced pegs may constitute a hazard when left on the floor,

and they may become lost. To obviate this condition, I provide stop means for preventing withdrawal of the pegs from the board. Referring to Figs. 4 and 5, this stop means includes a vertical groove or recess routed in one of the vertical sides of each peg 35. A small nail 39 is driven into one of the faces of each notch 30 with its small head projecting from said face in position to be received in the groove 38 of a peg inserted into the peg opening. The nail head is adapted to engage the ends of the groove 38 to limit the movement of the peg in either direction and thus is effective in preventing removal of the peg from the peg board. Thus, by this extremely simple and inexpensive means, loss of the pegs from the toy is avoided.

As will be apparent, the general structure of the toy as described above is applicable to peg board toys wherein conventional round dowel pegs are employed. However, for the reasons discussed herein, the use of square pegs is much preferred. Referring now to Fig. 7, it is within the concept of my invention to utilize a round metal peg 42 having a point 43 at one end and a head 44 at its opposite end. This peg is, in effect, a large nail which may be driven through a round peg opening, the point 43 being first inserted in the contracted peg opening and the nail then driven by striking the head 44, the board elements being forced apart by this action to permit such movement of the nail. After the peg nail 42 has been thus driven, it may be removed by the child by the use of the claw portion of a hammer which is operated in the usual manner. The toy is thus made even more fascinating to the young workman since the operation simulates that employed in carpentry.

In accordance with the provisions of the patent statutes, I have described the principle of operation of my device, together with components which I consider to represent the best embodiments thereof, but I desire to have it understood that the invention may be carried out by further modified means, within the spirit of the invention.

I claim as my invention:

1. A peg board toy, comprising: a pair of spaced, vertical end members; a pair of parallel side rails connected to and extending longitudinally between said end members; at least two sets of peg board elements supported by and extending transversely between said side rails, each set including an outer element abutting the inner side of one said end members, an inner element disposed substantially midway between said end members, and an intermediate element arranged between said outer and inner elements, the abutting edges of said elements having aligned vertical grooves together defining peg openings; interengaging slide means on said side rails and said peg board elements permitting longitudinal sliding movement of the latter toward and away from said end members; pegs disposed in said peg openings and adapted to be driven vertically therein; and spring means disposed between and engaging the inner elements of said sets of elements and operative to force said sets apart and toward a said end member, said spring means tending to yieldingly maintain the elements of each set in close juxtaposition so as to reduce the cross-sectional size of said peg openings and thus effect frictional resistance to vertical movement of said pegs in said openings.

2. A peg board toy, comprising: a pair of

75

8. A toy as defined in claim 3, including inter-

spaced, parallel, vertical end members; a pair of parallel side rails connected to and extending longitudinally between said end members; at least two sets of peg board elements supported by and extending transversely between said side rails, each set including an outer element abutting the inner side of one of said end members, an inner element disposed substantially midway between said end members, and an intermediate element arranged between said outer and inner elements, the abutting edges of said elements having aligned vertical grooves together defining peg openings; interengaging tongue-and-groove slide means on said side rails and said peg board elements permitting sliding movement of the latter toward and away from said end members; pegs disposed in said openings and adapted to be driven vertically therein; and spring means disposed between and engaging the inner elements of said sets of elements and operative to force said sets apart and toward a said end member, said spring means tending to yieldingly maintain the elements of each set in close juxtaposition so as to reduce the cross-sectional size of said peg openings and thus effect frictional resistance to vertical movement of said pegs in said openings.

3. A peg board toy, comprising: a pair of parallel, spaced, vertical end members; a pair of parallel side rails connected to and extending longitudinally between said end members, each side rail having a longitudinally extending rib; at least two sets of peg board elements supported by and extending transversely between said side rails, each set including an outer element abutting the inner side of one of said end members, an inner element disposed substantially midway between said end members, and an intermediate element arranged between said outer and inner elements, the abutting edges of said elements having aligned vertical grooves together defining peg openings, each of said elements having horizontal grooves in its lateral edges receiving said ribs of said side rails to permit sliding movement of said elements toward and away from said end members; and spring means disposed between and engaging the inner elements of said sets of elements and operative to force said sets apart and toward a said end member, said spring means tending to yieldingly maintain the elements of each set in close juxtaposition so as to reduce the cross-sectional size of said peg openings and thus effect frictional resistance to vertical movement of said pegs in said openings.

4. A toy as defined in claim 3 in which said spring means comprises a pair of coil springs having their ends seated in pockets provided in the facing edges of said inner elements of each set, said springs being compressed therebetween.

5. A toy as defined in claim 3 in which each side rail is T-shaped in cross section and has a vertical flange and a horizontal rib, the ribs of said rails being directed toward each other.

6. A toy as defined in claim 3 in which each of said grooves in said peg board elements is ninety-degree angular and defines, with the corresponding groove of an adjacent element, a substantially square peg opening, and in which said pegs are of square cross-sectional shape, the corners of the square pegs being rounded.

7. A toy as defined in claim 3 including interengaging stop means on said peg board elements and said pegs for limiting vertical movement of said pegs in said openings in at least one direction.

engaging stop means on said peg board elements and said pegs for limiting vertical movement of said pegs in said openings in either direction, so as to prevent withdrawal of said pegs from the toy.

9. A toy as defined in claim 8 in which said stop means consists of a vertical groove in the side of a said peg, and a stop elements carried by a said peg board element and projecting therefrom into a said vertical groove, said stop element being engageable with the ends of said vertical groove to limit vertical movement of said peg in either direction.
